DESIGN FOR A WRAPPING PAPER

Jean E. Vivaudou and Henry G. Lubin,
New York, N. Y.

Application March 1, 1940, Serial No. 90,609

Term of patent 7 years

To all whom it may concern:

Be it known that we, Jean E. Vivaudou and Henry G. Lubin, subject of Great Britain and citizen of the United States, respectively, and both residents of New York city, in the county of New York and State of New York, have invented a new, original, and ornamental Design for a Wrapping Paper, of which the following is a specification, reference being had to the accompanying drawing, forming a part thereof.

The figure is a face view of a wrapping paper, showing our new design.

We claim:

The ornamental design for a wrapping paper, as shown.

JEAN E. VIVAUDOU.
HENRY G. LUBIN.
